REED HOLDER FOR LOOMS

Application filed April 7, 1930. Serial No. 442,076.

This invention relates to improvements in reed holders for looms and it is the general object of the invention to provide a device between the reed proper and the hand rail to prevent wearing and chafing of the latter.

In certain looms, particularly those weaving silk, it is customary to solder the reed wires together at their upper and lower ends. Flat metallic strips may be fastened to the sides of the wires to present smooth surfaces, but the upper and lower ends are left rough or are only imperfectly soldered. When a reed having a bar rendered rough by protruding wires is placed in a reed cap or hand rail, wearing of the latter results. It is an important object of our present invention to provide an improved, preferably metallic, reed cap between the reed bar and the hand rail to prevent the aforesaid wearing.

In order to provide for slight variations which exist in the thickness of the reed and its bar we form the cap U-shaped in section with one of the vertical sides bowed or curved so as to be compressed when the reed is inserted, the degree of compression depending upon the width of the reed bar.

In certain instances it is desirable to be able to vary the width of the cap and in order to facilitate such an operation we provide the upper or horizontal part between the two vertical sides with an initial crimp extending longitudinally of the cap. This crimp affords a line of weakness which will permit the user, by employing a simple tool to press the sides together to adapt the cap to narrow slots in the hand rail. If the slot in the rail is too wide, the crimp may be flattened to spread the sides to the correct width to fit the wide slot.

With these and other objects in view which will appear as the description proceeds, our invention resides in the combination and arrangement of parts hereinafter described and set forth in the claims.

In the accompanying drawings wherein a convenient embodiment of our invention is set forth,

Fig. 1 is a vertical transverse section through a lay and hand rail having our invention applied thereto,

Fig. 2 is a fragmentary section on an enlarged scale showing the lower part of the hand rail and reed cap before the reed is put in position,

Fig. 3 is a view similar to Fig. 2 but with the reed in position,

Fig. 4 is a front elevation taken in the direction of arrow 4, Fig. 1, certain parts being broken away for the sake of clearness and showing a relatively short reed cap,

Fig. 5 is an operating view illustrating the manner in which the crimp or initial line of weakness is employed to lessen the width of the shell,

Fig. 6 is a perspective view of the reed cap, and

Fig. 7 illustrates the manner in which the crimp may be expanded or spread to widen the reed cap.

Referring to Fig. 1 we have shown a lay sword 10 supporting a lay 11 having a shuttle race 12. A backstay 13 may be provided with a notch 14 to receive a reed holder 15. The latter may be made as usual of a long relatively narrow wooden strip having a vertical slot therein to receive the lower bar of the reed.

An extension 16 projecting upwardly from the lay supports a hand rail 17 adjustable as to vertical position by means of a bolt 18 and winged nut 19. The under side of the hand rail has a slot 20 which may be substantially the same as that employed heretofore. The reed R may have an upper bar 21 substantially rectangular in vertical section and formed preferably of metal.

The matter thus far described is of common construction and forms no part of our present invention. The top of bar 21 may be rough as suggested in Figs. 2 and 4, being ribbed or roughened something like a file.

In carrying our invention into effect we provide one or more reed caps 30 shown in Fig. 6, having a straight vertical side 31 and a second vertical side 32 joined thereto by a horizontal connecting section 33. The side 32 may be bowed or curved as at 34 toward the opposite straight side. The section 33 may be provided with a longitudinal crimp or groove 35, and holes 36 may be provided for

tacks 37 or other securing devices which extend into the hand rail.

When assembling the reed cap will be pushed upwardly into the groove 20 with the straight side 31 to the rear or left of the slot 20 as viewed in Fig. 1 so that as the lay beats up there will be no yielding of the reed to interfere with the proper beating-in of the filling. The position of the cap will be 5 similar to that shown in Fig. 2, the tacks holding the same in position and the side 32 being bent toward the straight portion 31. The reed bar 21 will then be pushed upwardly between the two sides to bend the portion 32 10 forwardly against the front wall 38 of slot 20.

The cap is made of metal possessed of some resilience and when the curved part of the side 32 is straightened out against wall 38 it tends to hold the bar 21 tightly in position.

20 Any motion on the part of the reed with respect to the reed cap will take place along the interior surfaces of the cap and the latter will be held against relative movement with respect to the cap by tacks 37, so that 25 abrasion of the interior of the slot 20 is avoided.

Fig. 4 shows but one cap but in practice we may employ as many as are desired to give proper stiffness to the reed so that the 30 same will beat the filling into the cloth with a straight line. If desired one shell extending across the full width of the loom may be employed.

If upon assembly it is found that the slot 20 35 is slightly wider than the outside horizontal dimension of the cap, the groove or crimp 35 may be flattened out by means of a narrow tool inserted between the sides 31 and 32 as shown in Fig. 7, spreading said portions 40 apart so the cap will fill the groove. If on the other hand, the groove is found to be too narrow, a tool such as a pair of pliers suggested in Fig. 5 may be used to compress the vertical parts of the cap toward each other 45 until they are able to fit into the groove. The crimp is therefore seen to provide extra material which is available for winding the shell or provides a line of weakness which will facilitate reducing the horizontal dimension of 50 the shell. While we have shown the improved reed cap at the top only of the reed, yet we do not wish to be limited to this construction.

From the foregoing it will be seen that 55 we have provided a simple reed cap to be interposed between the reed and the hand rail to prevent wear of the latter. It will further be seen that a part of the cap is formed with a curved section sufficiently resilient to yield and permit entry of a reed bar, holding the 60 latter tightly in position with respect to the reed cap. Also, it will be seen that the cap is provided with a crimp or groove along the upper side thereof which may be employed either to widen or facilitate a narrowing of 65 the cap.

Having thus described our invention it will be seen that changes and modifications may be made therein by those skilled in the art without departing from the spirit and scope of the invention and we do not wish to be limited to the details herein disclosed, but what we claim is:

1. In a loom lay having a hand rail with a groove therein and a reed with a longitudinal bar, a reed cap formed of resilient material located in the groove and interposed between the hand rail and the bar and having a portion normally held under a stress exerted transverse of the plane of the reed by the bar to hold the latter resiliently in position. 70

2. In a loom lay having a hand rail with a groove therein and a reed with a longitudinal bar, a reed cap formed of resilient material located in the groove and interposed between the hand rail and the bar and having a portion normally held under a stress exerted transverse of the plane of the reed by the bar to hold the latter resiliently in position, 75 said part being on the front side of the reed bar. 80

3. In a loom lay having a hand rail with a groove therein and a reed with a longitudinal bar, a reed cap formed of resilient metallic stock and having two substantially parallel sides attached together by a connecting section, 85 said section having a longitudinal crimp defining an initial line of weakness to facilitate pressing of the two sides of the cap toward each other, the cap being interposed between the bar and the hand rail. 90

4. In a loom lay having a hand rail with a groove therein and a reed with a longitudinal bar, a reed cap substantially U-shaped in section having the opposite sides substantially parallel, and a connecting section attaching said sides together, said section being of some form other than flat to define an initial line of weakness to facilitate bending so that the sides may be readily pressed together, 100 said section also being capable of being interposed between the bar and hand rail. 105

5. In a loom lay, a hand rail formed of comparatively soft material and having a groove in the under side thereof, a reed having a rough bar of harder material located 110 in the groove, and a metallic reed cap in the groove and secured to the hand rail and interposed between the rough bar and hand rail. 115

6. A reed cap for a lay carried reed groove, 120 said cap being formed of resilient material substantially U-shaped in section and having one of the sides thereof curved toward the other side and capable of engaging one side of the groove and also the reed to be held under strain by the latter and thereby support a resilient mounting for the loom. 125

7. A reed cap for a lay carried reed groove, 130 said cap having a pair of sides attached together by a connecting section, said connect-

ing section having a crimp extending longitudinally of the cap and providing a line of weakness to facilitate pressing the sides of the cap together to fit a smaller groove.

5 8. A reed cap for a lay carried reed groove, said cap having a pair of lateral members, one of which is substantially straight to engage one side of the groove and the other of which is bent toward the straight member to engage that side of the reed opposite the straight member to hold the reed resiliently in position.

10 9. A reed cap for a lay carried reed groove, said cap having a pair of substantially parallel sides attached together by a connecting portion, the latter having a form other than flat to provide a part which when flattened out will tend to separate the sides of the cap.

15 In testimony whereof we have hereunto
20 affixed our signatures.

WILLIAM E. LUNDGREN.
